MIRROR SIGN WITH AN ELECTRIC CLOCK

Norman En Holm, New York, N. Y., assignor to
Multi Vue Signs Co., Inc., a corporation of New
York

Application July 9, 1937, Serial No. 152,700

12 Claims. (CL 40—132)

This invention relates to improvements in a mirror sign with an electric clock for advertising purposes or the like, the sign being of the type having a plurality of reflecting mirrors spaced apart from each other to produce multiple images of the indicia comprising the sign.

An object of the invention is to provide a sign of the character described in which the multiple images appear to move and thereby produce new and novel effects not heretofore obtainable.

Another object is to provide a sign of the character described of improved construction in which one or both of the moving mirrors therein cause circulation of air to take place within the sign casing, thereby cooling the operating parts.

A further object is to provide a sign of the character described having a clock face formed upon one of the mirrors of the sign and having an electric clock motor which may also be used to move one or both mirrors in the sign.

Other objects and advantages will appear from the following specification, it being understood that modifications, variations and adaptations may be made without departing from the invention hereinafter claimed.

In the accompanying drawings:

Figure 1 is an isometric view of the sign mirrors, one of which is movable;

Figure 2 is a top view of a complete sign embodying the invention;

Figure 3 is a sectional view on the line 3—3 of Figure 2;

Figure 4 is a horizontal view, partly in section, showing an alternative form of mounting the mirror and showing the position of the clock motor combined with a sign of the character described;

Figure 5 is a front view, partly in section, of a sign equipped with a clock;

Figure 6 is a sectional view of the stationary mirror 11 and movable mirror 14 showing how indicia 15^a may be applied to the rear of said last mirror;

Figure 7 is a view of the rear mirror 14 showing how the indicia 15^b may be applied to the front thereof;

Figure 8 is a diagrammatic view of a sign of the character described in which the indicia on the sign is produced by a reflection of an object placed in front of the sign the object being illuminated from the front; and

Figure 9 is a diagrammatic view of a sign of the character described in which the indicia on the sign is produced by projecting an image thereon from a suitable projector.

In the copending application filed July 9, 1937, Serial No. 152,698 is disclosed a sign of this general type in which the main feature of this invention—the movable mirror—is disclosed. The instant application relates to special forms of mounting for such movable mirrors and represents a further modification of the basic invention, and for the sake of illustration, a sign is herein described in which only one mirror is oscillated in the manner herein described. However, it will be obvious that both mirrors may be oscillated so that the mechanism and movement herein described may be combined with the mechanism and movements set forth in the aforesaid copending application to produce new and useful results, and that many modifications can be made in the device herein disclosed by combining the features herein shown with those shown in the copending application aforesaid.

It will further be observed that the instant application discloses the new and novel feature of combining an electric clock with a sign of the character described, and that the clock motor may be used for moving one or both mirrors in the sign.

Referring to Figure 3, the numeral 10 denotes a front casing of any suitable material and construction which supports a transparent mirror 11 which may consist of a sheet of glass or other transparent material provided with a thin coating 12 of silver on its rear face, which coating is just sufficient to form a reflecting surface by reflected light, and sufficiently thin to enable one to see through the glass. This mirror is held in the casing in any suitable manner, for example it may be held in top and bottom slots or grooves 13. Immediately in the rear of the mirror 11 but spaced a small distance therefrom is the rear mirror 14 having on its rear face a thick silver coating 15 which is not transparent to transmitted light. The indicia or advertising matter to be displayed by the sign to form movable multiple images may consist of any desired lettering, picture or design and is formed by removing the coating 15, leaving the plain glass 14 where the indicia is to appear, (see Figures 6 and 7).

The spaces so made are then coated (either on the front 15^b or rear 15^a of glass 14) if desired, with suitable transparent colors. This provides a translucent design on the rear mirror 14.

As more fully set forth in the copending application Serial No. 152,698 heretofore referred to, it will be observed that it is not necessary to have a light source within the casing de-

25

scribed in the instant application and that said casing, together with the two mirrors and the mechanism for moving one or both said mirrors, comprises a complete sign unit adapted to reflect in multiple images any object such as the indicia 15^a or 15^b herein described or any object either directly reflected in the mirrors or the image of which is projected thereon. For example, referring to Figure 8, if an object such as a bottle 33 5 is placed in front of the sign and illuminated by beams of light cast thereon from the lamps 34, 35, an image of this bottle will be reflected by the front translucent mirror 11 and an image is thereby formed on this mirror. This image is 10 likewise formed on the rear mirror 14 and multiple reflected images are produced without any indicia such as 15^a or 15^b appearing on the rear mirror.

Another way of utilizing the sign is to project 20 indicia thereon from any suitable source as a stereopticon 3^b, Figure 9, placed in front of the front mirror 11, the primary image being on a film or lantern slide of the ordinary type in the stereopticon. The image thus projected onto the 25 sign will be reflected in the manner just described.

It is apparent that in either case as just described, the sign may or may not have indicia 15^a, 15^b on the rear mirror.

30 The mirror 14 has secured thereto in any suitable manner two rearwardly extending supports 16, 16^a to which are connected the supporting rods 17, 17, 17^a, 17^a, which are hung in brackets 17^b secured to the top of the cabinet, 35 as shown in Figure 3. Guide rollers as shown at 17^c are provided for the supports 16, the arrangement being such that the mirror 14 is supported to swing from the position shown in solid lines, Figure 3 to the position 14^a shown in 40 dotted lines in said figure. This motion maintains the opposed surfaces of said mirrors substantially parallel to each other at all times. In order to move the mirror 14 any suitable means such as a small electric motor 18 may be employed and this may be mounted within the casing of the device and enclosed by the rear portion 19 thereof and the motor is connected in any suitable manner, as by the crank 20 at the point 21 to one of the supports 16. It will 50 be understood that the motor 18 may have any well known form of internal or external gearing so that the crank 20 will operate at the proper speed to produce the desired result. The translucent design on mirror 14 is adapted to 55 be illuminated by means of a suitable light source such as the electric lamps 22, 22^a which are mounted in the closed casing formed by 10 and 19.

With the mirrors arranged as above set forth 60 and with the design formed as described, light rays from the lamps 22, 22^a are directed through the translucent design on the rear mirror, and reflected images will be produced of said design and an image will be produced of the design at 65 a distance in front of the rear surface of the front mirror 11 which will be equal to the distance between the said rear face of mirror 11 and the rear face of the rear mirror 14. That image will in turn produce an image appearing 70 as far behind the rear face of mirror 14 as the first image is before the rear face of the mirror 14.

The second image will give rise to a further image by reflection from the mirrored rear surface of the front mirror 11 and these images 75

will be repeated and formed a multiple number of times directly behind one another and at a distance apart.

When the light rays from the lamps are projected through the rear mirror in this manner, part of said rays are transmitted through clear glass around the colored areas 15^b as indicated by the arrows, and therefore a greater illumination of the reflected images of the advertising design is produced and there will be obtained a 10 brilliantly lighted effect. The increase of illumination makes it possible to effect the production of a greater number of reflected images and therefore the illusion of the repetition of the advertisement is enhanced. 15

Such effects are old in the art where both mirrors have been stationary, the sign producing no illusion of motion, the lettering or other advertising being stationary. However, with the present invention, the motor 18 being in operation, the entire multiple image is apparently in motion, and the multiple image will apparently advance and recede in cycles as the mirror 14 moves toward and away from the mirror 11, which movement gives rise to effects heretofore 25 unobtainable and of such large variety and complexity depending on the letters, figures or other indicia used, that no attempt is made to describe them here.

A further modification of the sign as just described particularly useful when the sign is combined with the clock is shown in Figures 4 and 5 wherein the rear mirror 23 is pivoted at 24, 24^a so that it can be oscillated about a vertical axis. This mirror is connected at one end to crank 20 35 of the motor 18. With this embodiment of the invention it is very easy to add an electric clock to the unit assembly. This is accomplished by mounting the electric clock movement indicated at 32 so that the drive shaft 25 for the hands 40 will extend through a hole in the center of mirror 23 and outwardly through another hole in the center of mirror 11, this shaft or shafts carrying the usual clock hands 26, 27. The hour numerals 28 may be placed on the rear mirror 45 23 as previously described along with the advertising indicia or may be placed on the front or rear of the front mirror 11. In the event that said numerals are placed on the rear mirror they will be displaced when said rear mirror is moved 50 as indicated in Figure 5.

The clock motor 32 may be connected via a suitable shaft or any other means indicated at 29, Figure 4, to a gear (not shown) which would replace the motor 18 and therefore the electric 55 clock motor 32 may be used to oscillate the moving mirror 23.

Obviously, the clock arrangement just described can be used in connection with the sign construction shown in Figure 3 and obviously 60 by reference to the heretofore mentioned co-pending application, or to the co-pending application filed July 9, 1937 Serial No. 152,699 both mirrors may be moved.

A further improvement is disclosed in connection with Figure 3 wherein the casing 10 is provided with air ducts 30 and louvers 31 are provided in the rear casing 19. The movement of the mirror 14 which is bellows-like in action, will then cause a draft of air to circulate through 70 the casing, thereby cooling and ventilating the interior thereof.

While the term "translucent" has been applied to the indicia or design on one of the mirrors, it will be understood that any suitable in- 75

dicia or design may be employed, either translucent or opaque, and that such design may be applied wholly or partially on any of the surfaces of either of the mirrors or may be projected on the device from an outside source and reflected thereon.

The light source is shown as behind the rear mirror. It will be understood this light source may be located anywhere relative to the indicia, in order to illuminate the same, for example in front of the sign, or above or below the same. The location and method of illuminating the indicia can therefore be varied within wide limits.

What is claimed is:

1. In a sign of the character described, a pair of plane mirrors, means for continuously moving one mirror toward and away from the other mirror to produce constantly varying multiple reflections while maintaining the opposed surfaces of said mirrors substantially parallel, and means for illuminating said mirrors.

2. In a sign of the character described, a casing, a mirror fixed in said casing, a second mirror having a plane surface opposed to a plane surface of said first mirror, means secured to said casing for movably suspending said second mirror therefrom, means for continually moving said second mirror to produce constantly varying multiple reflections, and means for illuminating said mirrors.

3. In a sign of the character described, a casing, a mirror in said casing, a second mirror opposed to said first mirror, means for supporting said second mirror in said casing, means for moving said second mirror toward and away from said first mirror to produce constantly varying multiple reflections while maintaining the opposed surfaces of said mirrors in substantially parallel relationship, and means for illuminating said mirrors.

4. A sign as claimed in claim 3 wherein the means for moving said second mirror includes a reciprocating arm connected thereto and an electric motor connected to said arm to reciprocate the same.

5. A sign as claimed in claim 3 wherein said casing has ventilating apertures therein and said second mirror is adapted when moved to cause a circulation of air within said casing and said apertures.

6. A sign as claimed in claim 3 wherein said

casing is in two parts, each having apertures to permit air to circulate through said casing when said second mirror is moved therein to produce a bellows action therein.

7. In a sign of the character described, a pair of apertured mirrors one of which is translucent, said mirrors adapted to produce multiple reflections, means for continuously moving one of said mirrors, a clock movement positioned behind said mirrors and having a shaft extending outwardly through said apertures therein, clock face indicia on one of said mirrors, and a casing in which said mirrors are operatively supported.

8. A sign as claimed in claim 7 wherein the movable mirror is connected to the clock movement to be moved thereby.

9. A sign of the character described having a pair of mirrors one of which is translucent, said mirrors adapted to produce multiple reflections and having opposed reflecting surfaces, a casing supporting said mirrors, a clock enclosed by said casing having a face formed on one of said mirrors therein, and means for continuously moving one of said mirrors to cause the opposed surfaces of said mirrors to assume various relative angular positions whereby said multiple reflections are given apparent movement.

10. A sign of the character described having a pair of mirrors one of which is translucent, said mirrors adapted to produce multiple reflections, a casing supporting said mirrors, clock mechanism comprising clock hands overlying one of said mirrors, a clock face formed on one of said mirrors, and means for moving said last mirror to cause apparent movement of multiple reflections of said clock face.

11. In a device of the character described, a casing having a pair of mirrors therein the outer mirror being translucent, clock mechanism associated with said mirrors and supported by said casing, the hands of said clock overlying the outer face of said outer mirror, the rear mirror of said pair having translucent clock face indicia thereon, and means within said casing for illuminating said indicia to cause multiple reflections thereof to appear on said mirrors.

12. The device as claimed in claim 11 wherein one or both mirrors are moved by means located within said casing to cause said multiple reflections to appear to cyclically move.

NORMAN EN HOLM. 50
